DISPOSABLE DIAPERS

Evelyn H. Krusko, Newtown Square, Pa., assignor to Scott Paper Company, Delaware County, Pa.

Original design application Aug. 2, 1971, Ser. No.
168,529. Divided and this application Mar. 19,
1973, Ser. No. 342,603

Term of patent 14 years

Int. Cl. D24—04
U.S. Cl. D83—1 A

Fig. 3Fig. 4Fig. 5Fig. 6

FIG. 1 is a top plan view of a disposable diaper showing my new design, it being understood that the pattern uniformly continues over the entire top surface of the diaper;

FIG. 2 is a bottom view of the disposable diaper shown in FIG. 1, it being understood that the pattern uniformly continues over the entire bottom surface of the diaper;

FIG. 3 is an enlarged portion of the design as indicated by 3—3 in FIG. 1;

FIG. 4 is an enlarged portion of the design as indicated by 4—4 in FIG. 1;

FIG. 5 is a side elevation view taken in the direction of 5—5 of FIG. 1; and

FIG. 6 is a transverse sectional view taken along line 6—6 of FIG. 1.

This application is a division of U.S. design patent application Ser. No. 168,529, filed Aug. 2, 1971, and titled Disposable Diapers.

I claim:

The ornamental design for disposable diapers, as shown and described.
